Patented Oct. 16, 1928.

UNITED STATES PATENT OFFICE.

CLARENCE E. PALMER, OF FAYETTEVILLE, ARKANSAS.

PERPETUAL CALENDAR.

Application filed July 26, 1927. Serial No. 208,802.

The present invention relates to calendars and especially to that form known as a "perpetual calendar", namely: one which not only forms a calendar of the usual form for the current year, but also is readily adaptable for an indefinite number of years both in the past and in the future.

An important object of the invention is to provide a calendar which consists of certain features of novelty in the combination and arrangement of the parts, indicia, and digits comprising said calendar whereby a series of relatively fixed and relatively movable digits and indicia may be so combined in one general structure as to provide means whereby such structure is available for use as a calendar for a predetermined period of years as indicated by numerals in year charts arranged thereupon and made a part of the calendar.

20 The calendar is of simple form and consists of a single shiftable card whereby the digits indicative of the days of a month may be properly located in relation to columns at the top of which are indicia indicative of the days 25 of the week so that said digits will be properly located in relation to said digits in accordance with a particular year and month as may be determined by fixed columns having years 30 therein and columns on the back of the card having months therein so that the card may be shifted to place the columns with the months on the back of the card coincident with the columns having the proper year desired.

35 With the above and other objects in view, the invention consists in certain novel features of construction, and in the combination and arrangement of parts as will be hereinafter more fully described and claimed.

40 In the drawings:

Figure 1 is a plan view of the calendar showing the swinging part in a down position,

Fig. 2 is a similar view showing the card shifted,

Fig. 3 is a similar view showing the swinging part upwardly disposed,

Fig. 4 is a similar view to Fig. 3 showing the card shifted,

Fig. 5 is a vertical section taken centrally 50 through either Figure 1 or Figure 2.

Figure 6 is a plan view showing the front side of another embodiment of the calendar, and

Figure 7 is a rear plan view thereof.

55 Referring to the drawings in detail, it will be seen that the numeral 5 denotes a base

card to which is hingedly connected a pair of folded cards 6 in spaced relation. Each card 6 is folded over upon itself and the ends are preferably pasted to flexible elements 7 which are in turn pasted to the hinged longitudinal dimensions of the base card 5. A 60 slidable card 8 is mounted in the foldable cards 6 to slide from side to side and a tab 9 is provided for this purpose on the edge of the card 8 and 65 also functions as a stop to limit the movement of the card 8 in respect to the base card.

On the base card 5 there is printed longitudinally thereof in a row the days of the week as indicated at 10. On this card 5 below the 70 column 10 there is provided a plurality of columns as is shown at 11 having past, present and future years printed therein.

On one side of the shiftable card 8 there is 75 printed rows of digits indicative of the days of the week and on the other side of the shiftable card 8 there is printed indicia indicative of the months of the year.

It will be seen that the cards 6 with the shiftable card 8 may be swung from the position shown in Figs. 1 and 2 to that shown in Figs. 3 and 4. The tab 9 is utilized as a marker.

The digits on the card 8 are arranged in 80 respect to the indicia indicative of the months of the year so that said card may be shifted to register the columns in which the months may be found to be continuations of the columns in which the desired year may be 85 found at 11. Thus if it is desired to find what day of the week a certain day in December fell on, in say the year 1873, it would be necessary to first swing the cards 6 to an up 90 position and register the column having the month December noted therein with the column having the year 1873 noted therein as is 95 illustrated in Fig. 3 and then the folded cards 6 may be swung down to the position shown in Figure 1 and we will have the calendar month for December, 1873.

100 Particular attention is directed to the convenience of the device and the ease with which it may be adjusted. Attention is also directed to the fact that the calendar may be used for every day purposes, it only being necessary to shift the same each month and therefore the calendar is just as handy as any ordinary calendar besides having the advantage of being useful in finding other useful data for which any ordinary calendar 105 would be insufficient.

110 In Figures 6 and 7 another embodiment

of the invention has been disclosed and referring thereto in detail, it will be seen that the numeral 5' denotes a base card provided with a pair of spaced parallel slits 4 through 5 which are slidable a card 8 having thereon digits 11' arranged in rows and indicative of the days of the month and at the bottom thereof in the columns formed by the digits suitable indicia indicative of months of the 10 year as denoted at 12'. On the base card 5 above the card 8' there is a row indicative of the days of the week as denoted at 10' while below the card 8' on the card 5 there is arranged a year chart as indicated at 13'. 15 Another year chart 14' is formed on the rear of the card 5' and is supplemental to the year chart 13'. The card 8' has a rivet 3 extended therethrough which is adapted to engage the edges of the slits 4 to limit the sliding movement of the card 8'. The use of this embodiment of the invention will be quite apparent from a consideration of the first embodiment described.

The present embodiments of the invention 25 have been disclosed in detail merely by way of examples since in actual practice they attain the features of advantage enumerated as desirable in the statement of the invention and the above description. It is apparent that changes in the details of construction, and in the combination and arrangement of parts may be resorted to without departing from the spirit or scope of the invention as hereinafter claimed or sacrificing any of its advantages.

Having thus described my invention what I claim as new is:

1. A calendar of the class described includ-

ing a base card, a pair of cards hingedly engaged in spaced relation with the base card, 40 each of said pair of cards including a pair of folds, a slideable card mounted to slide in the folds of said pair of cards.

2. A calendar of the class described including a base card, a pair of cards including folds and hingedly engaged in spaced relation with the base card, a slideable card mounted to slide in the folds of said pair of cards, a tab extending from one edge of the slideable card to abut said pair of cards to 50 limit the movement of the slideable card and to provide means for manually shifting said slideable cards, said base card having indicia thereon indicative of the days of the week and columns having therein indicia indicative of a plurality of years, said slideable cards having mounted on one face indicia indicative of the days of the month and on the other face indicia indicative of the months of the year. 60

3. A device of the class described including a base card, a slideway member swingably mounted on the base card and a slideable card in the slideway member, said base card having thereon indicia indicative of 65 the days of the week and indicia arranged in columns indicative of a plurality of years, said slideable card having on one face digits indicative of the days of the month and on its other face indicia indicative of the 70 month of the year arranged in columns registrable with the columns containing the indicia indicative of the years on the base card.

In testimony whereof I affix my signature.

CLARENCE E. PALMER.
